UNITED STATES PATENT OFFICE.

LEO SONDEREGGER, OF NEW YORK, N. Y., ASSIGNOR OF ONE-HALF TO WILLIAM MEYER, OF NEW YORK, N. Y.

WINDOW-CLEANER.

1,104,565.

Specification of Letters Patent. Patented July 21, 1914.

Application filed May 2, 1913. Serial No. 765,061.

To all whom it may concern:

Be it known that I, LEO SONDEREGGER, a citizen of the United States, and a resident of the city of New York, (Crotona Park, 5 east, borough of the Bronx,) in the county and State of New York, have invented a new and Improved Window-Cleaner, of which the following is a full, clear, and exact description.

10 The object of the invention is to provide a new and improved window cleaner arranged for convenient attachment to a window sill for effectively cleaning simultaneously both the outer and inner faces of the 15 panes of the lower and upper sashes.

In order to accomplish the desired result use is made of a support arranged for attachment to the window sill, a transverse spring-pressed shaft journaled on the said 20 support, inner and outer bars attached to the said shaft, inner and outer wiper arms pivotally connected with the outer ends of the said bars to swing transversely, a sleeve mounted concentrically relative to the said 25 shaft and provided with integral arms, inner and outer links connecting the said wiper arms with the said sleeve arms, and wipers held on the free ends of the said wiper arms. Each of the wipers referred

30 to consists essentially of a frame provided with a rubbing plate over which passes a wiping web unwinding from one roller and winding up on another roller to present new wiping surfaces to the window pane faces.

35 A practical embodiment of the invention is represented in the accompanying drawings forming a part of this specification, in which similar characters of reference indicate corresponding parts in all the views.

40 Figure 1 is a side elevation of the window cleaner; Fig. 2 is an enlarged cross section of the same on the line 2-2 of Fig. 1; Fig. 3 is a plan view of the same with parts in section on the line 3-3 of Fig. 1; Fig. 4 is a 45 cross section of the same on the line 4-4 of Fig. 1 and as applied to a window, parts being shown in section and parts being shown broken out; Fig. 5 is a sectional side elevation of the window cleaner on the line 5-5 50 of Fig. 3; Fig. 6 is an enlarged cross section of the outer wiper; Fig. 7 is an edge view of a modified form of the wiper; Fig. 8 is a plan view of the same with parts shown in section; Fig. 9 is a cross section of another 55 modified form of the wiper on the line 9-9

of Fig. 10; and Fig. 10 is a sectional side elevation of the same on the line 10-10 of Fig. 9.

The window cleaner is mounted on a support A, preferably in the form of a bar 60 adapted to extend across the window sill B, as indicated in Fig. 2, the support being provided with a depending lug A' adapted to engage the lower edge of the bottom stop bead of the sill B. The inner face of the 65 window sill B is adapted to be engaged by a head A² held on a screw A³ screwing in a nut A⁴ adjustably attached to an extension bar A⁵ pivoted at A⁶ to the inner end of the support A. A removable pin A⁷ is adapted 70 to engage one of a series of apertures A⁸ in the extension bar A⁵, the pin A⁷ also engaging the nut A⁴ so as to hold the latter adjustably on the extension bar A⁵ to allow of conveniently adjusting the support to different 75 widths of sills B. Thus for a very wide sill the nut A⁴ is moved outward on the extension bar A⁵ and then the screw A³ is screwed up to cause the head A² to engage the inner face of the sill B. For a narrow 80 sill the nut A⁴ is moved inward on the extension bar A⁵, and then the screw A³ is screwed up for clamping the support in place on the sill.

The support A is provided with upwardly 85 extending bearings A⁹ in which is journaled a shaft C to which are secured the inner and outer bars D and D' spaced apart to readily accommodate the lower and upper sashes E and E' between them at the time 90 the support A is fastened in place on the window sill B. The outer ends of the bars D and D' are provided with brackets F, F' having transversely extending members F², F²', on which are pivoted inner and outer 95 wiper arms G, G' provided at their upper ends with wipers H and H' adapted to engage the inner and outer surfaces of the pane of the lower or upper sash operated on at the time. The brackets F and F' are provided 100 at their upper ends with pins F⁴, F⁵ (see Figs. 3 and 4), pivotally connected with bars I, I' arranged parallel to the bars D and D', the bars I, I' being pivotally connected with arms J, J' extending integrally from a sleeve 105 J² mounted to turn loosely on a sleeve K arranged on the shaft C (see Fig. 2). By the arrangement described a double parallel frame is provided which can be swung up or down with the shaft C as a fulcrum, and 110

the arms G, G' can be swung sidewise so that the wipers H and H' reach every portion of the inner and outer surfaces of the sash pane. The pins F⁴, F⁵ previously mentioned are slidingly engaged by the arms G and G' so as to limit the transverse swinging movement of the said arms G and G'. Springs F⁶, F⁷ are coiled on the pins F⁴, F⁵ and press against the arms G, G' so as to normally hold the same in outermost position, that is, with the wipers H, H' out of engagement with the faces of the window pane.

In order to counterbalance the parallel frame with the wiper arms and wipers, use is made of a torsion spring L coiled on one end of the shaft C (see Figs. 2 and 3) and having one end resting on the support A and the other end attached to a collar L' ad- justably secured to the shaft C by a set screw L² to allow of increasing or decreasing the tension of the spring L so as to properly counterbalance the parallel frame, the wiper arms G, G' and the wipers H, H'.

The inner wiper H is mounted on a frame H² having a shaft H³ journaled in a bearing G² held on the upper end of the inner wiper arm G. The shaft H³ terminates in a downwardly extending handle H⁴ adapted to be taken hold of by the operator with the right hand for imparting an up and down swinging motion to the parallel frame and a side- wise swinging motion to the wiper arm G and a turning motion to the wiper H. A rubbing plate N is attached to the frame H² by a universal joint N' and the rubbing plate N is provided with a pad N² of felt or other suitable material, and over which passes a web N³ of muslin or other suitable material. The web N³ unwinds from a roller N⁴ and winds up on a roller N⁵, both rollers N⁴, N⁵ being journaled in suitable bearings arranged on the wiper frame H². The roller N⁴ is located below the shaft H³ while the roller N⁵ is located above the said shaft and is provided at one outer end with a knurled head N⁶ (see Fig. 1) adapted to be taken hold of by the operator for turning the roller N⁵ so as to wind up the web N³ and thereby draw the same over the pad N² with a view to present clean wiping surfaces to the inner face of the window pane.

The wiper H' is provided with a frame O mounted to turn on the upper end G³ of the arm G', and on the said frame O is pivoted at O' a rubbing plate O² provided with a pad O³ of felt or other suitable material. Over the pad O³ passes a web O⁴ unwinding from a roller O⁵ journaled on the frame O. The web O⁴ winds up on a roller O⁶ (see Figs. 5 and 6) journaled in the frame O. A spring O⁷ is attached to the frame O and presses against the upper portion of the rubbing plate O² so as to hold that portion of the web O⁴ which is stretched over the pad

O³ in firm contact with the outer surface of the window pane, as will be readily understood by reference to Fig. 6.

The web O⁴ is automatically wound up on the roller O⁶, and for this purpose the following arrangement is made: On the roller O⁶ is secured a ratchet wheel P (see Figs. 4 and 5) engaged by a pawl P' fulcrumed on a bell crank lever P² mounted to swing loosely on the roller O⁶ as a fulcrum. A spring P³ connects the frame O with the bell crank lever P² so as to impart a return swinging motion to the bell crank lever P², as hereinafter more fully described. The lever P² is preferably of U shape to provide a support for a guide roller P⁴ for the web O⁴, which latter also passes over a guide rod O⁸ held at the rear of the frame O, as plainly indicated in Figs. 4 and 6. The bell crank lever P² is provided with a depending link P⁵ on which is pivoted a depending link Q provided at its lower end with ratchet teeth Q' adapted to engage a keeper Q² pivoted at Q³ on the bracket Q⁴ attached to the connecting bar I'. A spring Q⁵ bears on the back of the link Q so as to normally hold one of the teeth Q' in engagement with the keeper Q², the spring Q⁵ permitting the operator to swing the link Q out of engagement with the keeper Q² whenever it is desired to fold the window cleaner.

When the device is in use and a swinging motion is given to the arm G' by means of handle H⁴ then the link Q, held in engagement with the keeper Q², causes a downward swinging of the bell crank lever P², at the time the arm G' swings from the left to the right beyond a vertical position, thus causing the pawl P' to turn the ratchet wheel P and the roller O⁶ to wind up the web. When the wiper arm G' swings back the pawl P' glides over the ratchet wheel until the wiper arm G' has returned to vertical position.

Thus by the arrangement described an intermittent turning motion is given to the roller O⁶ on giving a swinging movement to the arm G' so as to wind up the web O⁴ whereby the web O⁴ is drawn over the pad O³ and consequently a new wiping surface is continually presented to the outer face of the window pane. A spring Q⁶ connects the bracket Q⁴ with the bracket F³ (see Figs. 3, 4, and 5) to counterbalance the arm G' at the time the latter is swung from vertical position over to the left, it being understood that during this movement the spring Q⁶ is placed under tension.

In order to impart a transverse swinging movement to the outer wiping arm G', the following arrangement is made: A bracket G⁴ is attached to the wiper arm G' near the upper end thereof and to this bracket is secured one end of a rope, cable or other flexible connection R which ex-

- tends downward and passes around a guide pulley R' journaled on the free end of the bar D' . The flexible connection R is preferably provided with an interposed spring R^2 (see Fig. 5) and passes under a guide pulley R^3 to then connect with the peripheral face of a cam K' secured to or forming part of the sleeve K , previously mentioned, and mounted to turn loosely on the shaft C .
- 5 On one end of the sleeve K is secured a ratchet wheel K^2 engaged by a pawl K^3 fulcrumed on a handle K^4 mounted to swing loosely on the sleeve K as a fulcrum. A dog K^5 engaging the ratchet wheel K^2 is
- 10 fulcrumed on the bar D and is provided with a lug K^6 (see Fig. 1) adapted to be engaged by the heel of the pawl K^3 so as to swing the dog K^5 out of engagement with the ratchet wheel K^2 at the time the handle
- 15 K^4 is swung from the left to the right, with the pawl K^3 gliding over the said ratchet wheel K^2 . When the operator swings the handle K^4 from the right to the left the pawl K^3 turns the ratchet wheel K^2 and
- 20 consequently the sleeve K which by the cam K' exerts a pull on the flexible connection R so that a transverse swinging movement is given to the wiper arm G' toward the window pane to move the web O^4 overlying the
- 25 pad O^3 in firm engagement with the window pane so as to wipe the outer face thereof clean on imparting a corresponding movement to the wiper H' through the action of the operator manipulating the handle H^4 in
- 30 swinging the parallel frame and the arms G and G' , as previously explained.
- 35 In using the device the operator raises the lower window sash and then places the support A transversely in position on the window sill and fastens the support thereon as previously explained. Either of the two sashes is now moved into lowermost position so as to extend between the arm G and its wiper H and the arm G' and its wiper
- 40 H' . The operator now takes hold, with the right hand, of the handle H^4 , and, with the left hand, of the handle K^4 , and by bearing on the handle H^4 in a transverse direction the wiper H is moved in contact with the
- 45 inner surface of the window pane, and by the operator swinging the handle K^4 to the left the arm G' is swung transversely toward the window pane to move the wiper H' in contact with the outer face of the window pane. The operator by manipulating the handle H^4 now moves the wiper over the
- 50 surface of the window pane, it being understood that every portion of the window pane can be reached owing to the connection of
- 55 the arms G , G' with the parallel frames. In case it is a very large window the support A with the parts mounted thereon can be shifted lengthwise on the window sill so as to permit of cleaning the window pane in
- 60 sections according to the range of the win-
- dow cleaner. It is understood that the operator in charge can periodically turn the knurled head N^6 so as to present a new surface of the web N^3 to the window pane, but a new surface of the web O^4 is presented to 70 the outer face of the window automatically by the action of the pawl and ratchet mechanism P , P' connected with the winding up roll O^6 and controlled by the link Q in engagement with the keeper Q^2 as previously 75 explained.
- The rubbing plates N and O^2 are pivotally connected with their frames H^2 and O to insure a proper contact of the portions of the webs N^3 , O^4 passing over the pads N^2 80 and O^3 with the inner and outer surfaces of the window pane, so that a very effective cleaning of the window pane surfaces is had when using the machine as above explained. By bearing with more or less force 85 on the handle K^4 a corresponding contact of the wiper H' is had with the outer face of the window pane.
- The modified outside wiper H' shown in Figs. 7 and 8, consists essentially of a web S unwinding from a roller S' and winding up on a roller S^2 provided with a knurled head S^3 for turning the roller S^2 by the operator. The web S^2 is adapted to pass over a pad S^4 attached to a rubbing plate S^5 95 hinged at S^6 to a frame T provided with a shaft T' journaled on a bracket G^5 attached to the upper end of a wiper arm G' . The shaft T' carries brackets T^2 , T^3 in which the rollers S' and S^2 are journaled. Flat 100 springs T^4 , T^5 are attached to the bracket T^2 and bear against the back of the rubbing plate S^5 so as to insure a proper flat contact of the rubbing surface of the web S with the outer face of the window pane.
- 105 In the modified form shown in Figs. 9 and 10 the web U unwinds from a roller U' and winds up on a roller U^2 provided with a knurled head U^3 under the control of the operator. The rollers U' and U^2 are journaled on a frame U^4 straddling a bearing U^5 mounted to turn on a pin G^6 , the bearing being pivoted at U^7 to the rubbing plate U^6 , and the said rubbing plate U^6 is pressed on by a spring U^{10} to hold the surface of the 110 web U extending over the pad U^9 in firm contact with the outer face of the window pane. A link U^8 connects the outer ends of the journals of the rollers U' and U^2 with each other to give the desired strength to the 115 frame U^4 .
- 120 It is understood that in the modified forms shown in Figs. 7, 8, 9 and 10, the automatic turning device of the winding up roller is entirely dispensed with and the web U is adjusted to present a clean surface prior to starting cleaning of the outer surface of the window pane of a lower or upper sash.
- 125 Having thus described my invention, I 130

claim as new and desire to secure by Letters Patent:

1. A window cleaner, comprising a support arranged for attachment to a window sill, a spring-pressed shaft arranged to extend transversely of the window sill and journaled on the said support, inner and outer bars attached to the said shaft, inner and outer wiper arms pivotally connected with the outer ends of the said bars, a sleeve mounted concentrically relative to the said shaft and provided with integral arms, inner and outer links connecting the said wiper arms with the said sleeve arms, and wipers held on the free ends of the said wiper arms. 10
2. A window cleaner, comprising a support arranged for attachment to a window sill, a spring-pressed shaft arranged to extend transversely of the window sill and journaled on the said support, inner and outer bars attached to the said shaft, inner and outer wiper arms pivotally connected with the outer ends of the said bars, a sleeve mounted concentrically relative to the said shaft and provided with integral arms, inner and outer links connecting the said wiper arms with the said sleeve arms, wipers held on the free ends of the said wiper arms, a handle on the said inner wiper arm, and 15 manually-controlled mechanism connected with the said outer wiper arm for imparting a transverse swinging movement to the said outer wiper arm. 20
3. A window cleaner, comprising a support arranged for attachment to a window sill, a spring-pressed shaft arranged to extend transversely of the window sill and journaled on the said support, inner and outer bars attached to the said shaft, inner and outer wiper arms pivotally connected with the outer ends of the said bars, a sleeve mounted concentrically relative to the said shaft and provided with integral arms, inner and outer links connecting the said wiper arms with the said sleeve arms, wipers held on the free ends of the said wiper arms, a handle on the said inner wiper arm, a flexible connection connected with the said outer wiper arm, guides on the said outer bar for guiding the said flexible connection, a cam to which the said flexible connection is attached, a cam sleeve mounted to turn on the said shaft and carrying the said cam, and a handle for operating the said cam sleeve. 25
4. A window cleaner, comprising a support arranged for attachment to a window sill, a spring-pressed shaft arranged to extend transversely of the window sill and journaled on the said support, inner and outer bars attached to the said shaft, inner and outer wiper arms pivotally connected with the outer ends of the said bars, a sleeve mounted concentrically relative to the said shaft and provided with integral arms, inner and outer links connecting the said wiper arms with the said sleeve arms, and wipers held on the free ends of the said wiper arms, each wiper having a rubbing plate, an endless wiping web passing over the said plate and winding up and unwinding rollers on which winds and unwinds the said web. 30

and outer links connecting the said wiper arms with the said sleeve arms, wipers held on the free ends of the said wiper arms, a handle on the said inner wiper arm, a flexible connection connected with the said outer wiper arm, guides on the outer bar for guiding the said flexible connection, a cam to which the said flexible connection is attached, a cam sleeve mounted to turn on the said shaft and carrying the said cam, a handle loose on the said cam sleeve, a pawl on the said handle, and a ratchet wheel secured on the said cam sleeve and engaged by the said pawl. 70

5. A window cleaner, comprising a support arranged for attachment to a window sill, a spring-pressed shaft arranged to extend transversely of the window sill and journaled on the said support, inner and outer bars attached to the said shaft, inner and outer wiper arms pivotally connected with the outer ends of the said bars, a sleeve mounted concentrically relative to the said shaft and provided with integral arms, inner and outer links connecting the said wiper arms with the said sleeve arms, and wipers held on the free ends of the said wiper arms, each wiper having a rubbing plate, an endless wiping web passing over the said plate and winding up and unwinding rollers on which winds and unwinds the said web. 80

6. A window cleaner, comprising a support, arranged for attachment to a window sill, a spring-pressed shaft arranged to extend transversely of the window sill and journaled on the said support, inner and outer bars attached to the said shaft, inner and outer wiper arms pivotally connected with the outer ends of the said bars, a sleeve mounted concentrically relative to the said shaft and provided with integral arms, inner and outer links connecting the said wiper arms with the said sleeve arms, wipers held on the free ends of the said wiper arms, each wiper having a rubbing plate, an endless wiping web passing over the said plate and winding up and unwinding rollers on which winds and unwinds the said web, and means controlled by the said outer arm and the said outer link for turning the outer winding up roller. 100

7. A window cleaner provided with a wiper, comprising an arm, a frame mounted to turn on said arm, a rubbing plate pivotally connected with the said frame, rollers journaled on the said frame, and a web passing over the said rubbing plate and winding up on one roller and unwinding from the other roller. 110

8. A window cleaner, comprising a support arranged for attachment to a window sill, a spring-pressed shaft arranged to extend transversely of the window sill and journaled on the said support, inner and outer 120

125

130

bars attached to the said shaft, inner and outer wiper arms pivotally connected with the outer ends of the said bars, a sleeve mounted concentrically relative to the said shaft and 5 provided with integral arms, inner and outer links connecting the said wiper arms with the said sleeve arms, wipers held on the free ends of the said wiper arms, each wiper having a rubbing plate, an endless wiping web 10 passing over the said plate and winding up and unwinding rollers on which winds and unwinds the said web, a ratchet wheel on the outer winding up roller, a lever mounted to swing loosely on the said winding up 15 roller, a pawl on the said lever and engaging the said ratchet wheel, a link connected with the said lever and provided with ratchet wheels, and a keeper held on the said outer bar and engaged by the ratchet teeth of the 20 said link.

9. A window cleaner, comprising a support, arranged for attachment to a window sill, a spring-pressed shaft arranged to extend transversely of the window sill and 25 journaled on the said support, inner and outer bars attached to the said shaft, inner and outer wiper arms pivotally connected

with the outer ends of the said bars, a sleeve mounted concentrically relative to the said shaft and provided with integral arms, inner and outer links connecting the said wiper arms with the said sleeve arms, wipers held on the free ends of the said wiper arms, each wiper having a rubbing plate, an endless wiping web 30 passing over the said plate and winding up and unwinding rollers on which winds and unwinds the said web, a ratchet wheel on the outer winding up roller, a lever mounted to swing loosely on the said winding up roller, a pawl on the said lever and engaging the said ratchet wheel, a link connected with the said lever and provided with ratchet teeth, a keeper held on the said outer bar and engaged by the ratchet teeth of the said link, and a spring 35 pressing the said link to hold the link in engagement with the said keeper.

In testimony whereof I have signed my name to this specification in the presence of two subscribing witnesses.

LEO SONDEREGGER.
